UNITED STATES PATENT OFFICE.

THOMAS J. STEARNS, OF BOSTON, MASSACHUSETTS, ASSIGNOR TO THE
ROXBURY CARPET COMPANY, OF SAME PLACE.

DESIGN FOR A CARPET.

SPECIFICATION forming part of Design No. 12,931, dated May 16, 1882.

Application filed March 16, 1882. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

My design consists of a light ground ornamented with sunflowers and elongated leaves and partly covered by angular overlapping figures, variously ornamented, the ornamentation being mainly conventional. The arrangement of the overlapping figures is such that the ground is broken by them into detached masses, on which the sunflower ornamentation

is seen, the sunflowers being partially covered by some of the angular figures. The design also comprises trailing flowering vines, partly covering and relieving the angularity of some of the angular figures.

I claim—

The design for a carpet, substantially as shown and described.

In testimony whereof I have signed my name to this specification, in the presence of two subscribing witnesses, this 9th day of March, 1882.

THOMAS J. STEARNS.
